UNITED STATES PATENT OFFICE

CHARLES LOUIS MEYER, OF OMAHA, NEBRASKA, ASSIGNOR TO CONCRETE ENGINEERING COMPANY, OF OMAHA, NEBRASKA, A CORPORATION OF NEBRASKA

ROAD STRIP

Application filed March 6, 1930. Serial No. 433,530.

This invention relates to a parting or dividing strip used between two contiguous sections of a concrete or similar roadway or sidewalk. Such strips are usually made of sheet metal and are placed at the ends of adjoining sections or between the longitudinal edges of adjoining sections of concrete or similar material. The strip serves as a partition or confining wall and also as a contraction road strip to prevent cracks in the road bed due to contraction resulting from varying temperatures. In extreme cases the strip may not prevent cracking but in such instances it will at least confine the cracking to a positive direction and determination.

Strips of this nature as heretofore manufactured were usually constructed of a single strip of sheet metal deformed in some manner to provide a laterally projecting portion intermediate its longitudinal edges and adapted to be secured to the road bed by means of pins or stakes.

It is the purpose of this invention to provide such a strip but in such a manner as to permit of cheaper construction, greater rigidity and greater ease in handling and shipping.

In accordance with this invention the contraction strip is constructed of one or more longitudinal sections supported upon and secured together by short joining members or battens at proper intervals. The strips are preferably flanged and the securing or supporting members or even the flanges of the longitudinal members may be apertured to receive securing stakes or pins.

By the use of the spaced sections when two or more sections are used the reinforcing bars usually employed in a roadway may be inserted between the sections.

A better understanding of this invention will be obtained from a consideration of the following description given in connection with the drawings in which:

Fig. 1 is a plan view of a length of road or contraction strip and portions of two adjoining strips secured thereto.

Fig. 2 is a front elevation of the same.

Fig. 3 is a section on line 3—3 of Fig. 7.

Fig. 4 is a section on the line 4—4 of Fig. 2. Fig. 5 is a section along the line 5—5 of Fig. 2 showing a jointure of two strips.

Fig. 6 is a section along line 6—6 of Fig. 2.

Fig. 7 is a fragmentary perspective detail 65 illustrating the manner of securing two strips together and of securing the strips to the road bed.

Fig. 8 is a vertical section through a modified form of contraction strip embodying the 60 principles of this invention.

Fig. 9 is a fragmentary perspective detail of a still further modified form.

Fig. 10 is a section on line 10—10 of Fig. 9.

Fig. 11 is a fragmentary perspective of a 65 further modified form of this invention.

Fig. 12 is a section on line 12—12 of Fig. 11, and

Fig. 13 is a section on line 13—13 of Fig. 11.

Referring more particularly to the form of this invention illustrated in Figs. 1 to 7 inclusive it will be seen that the contraction road strip is formed of two angle irons or strips 1 and 2 held together in longitudinally 75 spaced relation to each other by channel shaped securing cross strips or battens 3. It will be noticed that the angle strips 1 and 2 are formed with their flanges bent at an angle less than 90° and are secured together by 80 cross strips 3 with their flanges inwardly opposing each other. The securing strips may be welded or otherwise secured at spaced intervals to the longitudinal strips 1 and 2. Strips 1 and 2 are substantially parallel converging at one end slightly an amount equal to the thickness of the strips. This will permit the telescoping together of the adjoining ends of the succeeding strips 1a and 2a, 85 and 1b and 2b. At one end these strips 1 and 2 are secured together by a keeper strip 4 which is offset outwardly to provide a flange 6 spaced from strips 1 and 2 the thickness of the strips to permit the insertion of the adjoining ends of the adjacent strips 1a and 2a. 95

It follows from the above that the road strips described due to the braced construction may be made of relatively light sheet metal which will permit economical manufacture and cheap transportation without 100

sacrificing rigidity and strength. The over all height of the road strip is slightly less than the over all thickness of the road in order that the upper edge will be slightly below the top surface of the road or pavement. The road strip may be secured to the road bed in upright position by means of stakes 7 U-shaped in cross section. These stakes may be driven through the channels of the securing strips 3 as is clearly shown in Figures 3, 6 and 7.

Referring to Fig. 8 the construction there shown is substantially the same as that shown in Figs. 1 to 7 with the exception that the two strips indicated by numerals 11 and 12 have their flanges bent at right angles. As in the prior modification the two strips are secured together by cross members 13.

In Figs. 9 and 10 there is shown a modification in which a single angle iron or strip 16 is employed and is supported by channeled cross strips 17. The latter strips are flanged outwardly as at 18 to form a foot rest for the completed strip. In this form the end cross strip 19 is also flanged at its base to provide a footing and is further flanged at its upper edge to provide a tongue 21 offset from the strip 16 and between which the adjoining strip 16a may be fitted.

In Figs. 11, 12 and 13 there is illustrated a still further modified form in which a pair of spaced angle irons or strips 23 and 24 are employed, the latter strips being secured together by flat cross strips 26. In this modification instead of the cross or securing strips being channeled to receive the supporting stakes the flanges of strips 23 and 24 are provided with aligned apertures to receive stakes 7.

It follows from the above descriptions that there are provided several forms of road strips which may be used either longitudinally or transversely across a roadway or pavement and which may be constructed of relatively light materials without sacrificing strength or rigidity and that the strips may be rigidly secured to the road bed in upright position.

It is obvious that many changes may be made in the details of construction without departing from the spirit and scope of the invention as defined in the claims appended hereto.

I claim:

1. A road strip comprising a pair of substantially parallel longitudinally spaced angle strips and channel-shaped cross strips secured at intervals to the plane surfaces of said angle strips, said cross strips being formed to receive securing stakes.
2. A road strip comprising a pair of substantially parallel longitudinally spaced angle strips, channel-shaped cross strips secured at intervals to the plane faces of said angle strips and substantially perpendicular there-

to, said cross strips being formed to receive securing stakes, and a keeper strip extending across said angle strips adjacent one end thereof, said keeper strip having an offset flange adapted to receive the ends of an adjoining pair of angle strips. 70

3. A road strip comprising a pair of substantially parallel longitudinally spaced angle strips and cross strips secured to the plane faces of said angle strips at intervals intermediate their ends, said angle strips being secured in spaced relation with their flanges extending in one direction and being opposed to each other, the opposed flanges being apertured to receive securing stakes therethrough. 75

4. A road strip comprising a pair of longitudinally flanged strips the flanges thereof extending at right angles therefrom and supporting strips secured at intervals to the plane faces of said flanged strips, said latter strips being of channel shape to receive securing stakes. 80

5. A road strip comprising a pair of longitudinally flanged strips the flanges thereof extending laterally from the strips at an angle less than 90° and supporting strips secured at intervals to the plane faces of said flanged strips, said latter strips being of channel shape to receive securing stakes. 90

6. A road strip comprising a relatively long strip flanged along one longitudinal edge thereof and supporting strips secured at intervals to the plane faces of said longitudinal strip, said supporting strips being flanged laterally at their ends to provide footings. 95

7. A road strip comprising a relatively long strip flanged along one longitudinal edge thereof and supporting strips secured at intervals to the plane faces of said longitudinal strip, said supporting strips being of channel shape. 100

8. A road strip comprising a relatively long strip flanged along one longitudinal edge thereof and supporting strips secured at intervals to the plane faces of said longitudinal strip, said supporting strips being of channel shape and having their free ends flanged laterally to provide footings. 105

In witness of the foregoing I affix my signature. 115

CHARLES LOUIS MEYER.
